Primary Examiner — Brian N. Vinson(74) *Attorney, Agent, or Firm* — Knobbe Martens Olson & Bear LLP(57) **CLAIM**

The ornamental design for an umbrella attached light, as shown and described.

DESCRIPTION

FIG. 1 is a top perspective view of an umbrella attached light. FIG. 2 is a bottom perspective view of the umbrella attached light of FIG. 1.

FIG. 3 is a front view of the umbrella attached light of FIG. 1;

FIG. 4 is a back view of the umbrella attached light of FIG. 1;

FIG. 5 is a left view of the umbrella attached light of FIG. 1;

FIG. 6 is a right view of the umbrella attached light of FIG. 1;

FIG. 7 is a top view of the umbrella attached light of FIG. 1; and,

FIG. 8 is a bottom view of the umbrella attached light of FIG. 1.

The broken line disclosure represents portions of the light which form no part of the claimed design.
